UNITED STATES PATENT OFFICE.

FREDERICK C. OVERBURY, OF NEW YORK, N. Y., ASSIGNOR TO THE FLINTKOTE COMPANY, OF BOSTON, MASSACHUSETTS, A CORPORATION OF MASSACHUSETTS.

COVERING FOR ROOFS AND SIDE WALLS.

1,270,654.

Specification of Letters Patent. Patented June 25, 1918.

Application filed September 3, 1914. Serial No. 860,012.

To all whom it may concern:

Be it known that I, FREDERICK C. OVERBURY, a citizen of the United States, and resident of New York, in the county of New York and State of New York, have invented certain new and useful Improvements in Coverings for Roofs and Side Walls, of which the following is a specification.

The present invention has relation to waterproof and weather-proof coverings for roofs and side walls, and it has for its object to provide a covering which may be laid to produce various colored effects. Broadly speaking, the invention consists of a covering element, either a sheet or a shingle as the case may be, which is reversible end for end, and which is provided upon its face with two coatings of different shades, tints or colors, so that when the covering is laid in overlapping rows on the roof or wall the exposed surfaces will be either of two colors, tints or shades, or else will present alternating colors. In this way the purchaser or user will be able to secure any one of several different color effects. Heretofore to secure this result it has been necessary for the user to purchase coverings of different colors, and for the dealers to carry the same in stock.

Referring to the drawings:

30 Figure 1 represents a shingle formed of prepared waterproof weather-proof roofing material, and embodying the invention.

Fig. 2 shows how the shingles may be laid to produce the color effects.

35 Fig. 3 represents a sheet of covering material embodying the invention.

Fig. 4 shows the sheets in overlapping relation.

The covering may be made of any suitable materials, but preferably it consists of a sheet of fibrous material such as felt thoroughly impregnated with a waterproofing substance, for instance a hydrocarbon compound such as asphaltum, pitch or the like.

45 At least one of the faces of the sheet is coated or covered with a layer of weather-proof waterproof material such as pitch or asphaltum. This outer coating or facing between the top and bottom edges of the covering element (shingle or sheet) is divided into two parallel strips of different colors, tints or shades. This may be done in several ways, either by mixing differently colored pig-

ments with the facing compounds, or else by embedding granular material of different colors in the coating.

55 On the drawing, *a* indicates a flexible shingle formed in the manner I have described, the face thereof being provided with two parallel strips *b*, *b'* of coating material which are different in color. The line of division between these strips is preferably midway between and parallel to the top and bottom edges of the shingle. For example, the strip *b* may be green, or slate color, and the strip *b'* may be brown or red. In laying the covering, the shingles are arranged in horizontal overlapping rows, with the shingles of one row overlapping the upper strips of the next adjacent lower row. 70 Thus by placing the shingles, with all the strips *b* or *b'*, as the case may be, at the lower end thereof, the roof will present a surface of a single color. But by placing one row of shingles with the strips *b* exposed, and laying the next higher row with the strips *b'* exposed, the roof will present a banded appearance. However, the shingles may be otherwise laid to present geometrical designs, in colors, of great beauty,—this being 80 determined by the user.

It will be noted further that, when the shingles are laid laterally spaced as shown in Fig. 2, the portions of the next lower shingles, which are exposed by the spaces 85 between the shingles in each row being of different or contrasting colors, serve to accentuate the depth of the recesses and to give to the exposed portions of the shingles an appearance of thickness.

90 In Fig. 3, I have shown at *c* a portion of a sheet covering, this being likewise provided with parallel facing strips *d*, *d'* of different colors. Such sheets may be laid as indicated in Fig. 4, so that either of the 95 strips will be exposed below the overlapping sheet, to produce exposed surfaces of the same color, or to produce a banded appearance.

Having thus explained the nature of my 100 said invention and described a way of constructing and using the same, although without attempting to set forth all the forms in which it may be made or all the modes of its use, what I claim is:

105 1. A covering element, for roofs and side

walls, provided on its outer face with a layer of weather-proof waterproof material, said material being formed in two parallel strips of different colors between and parallel to 5 the top and bottom edges of the element, whereby said element may be laid to expose either of said strips.

2. A covering element for roofs and side walls, consisting of a shingle formed of 10 weather-proof waterproof material having between and parallel with its top and bottom edges two parallel strips of facing material of different colors, said strips being substantially equal in width, whereby when said 15 shingles are laid in overlapping horizontal rows the upper strips of each may be covered, and only the lower strips exposed.

3. As a new article of manufacture, a roofing element, comprising a waterproof 20 body of fibrous material having a weather-proof coating of different colors on opposite end portions of one of its surfaces.

4. As a new article of manufacture, a shingle of flexible material having a coating 25 of different colors on opposite end portions of one of its surfaces.

5. As a new article of manufacture, a shingle of flexible material having a coating of comminuted material on one surface 30 thereof, such coating being of different

colors on opposite end portions of such surface.

6. As an article of manufacture a shingle of flexible material having a coating of comminuted material over one entire surface 35 thereof, such coating being of different colors on the opposite end portions of said surface.

7. A shingle of flexible material having a coating of comminuted material over one 40 entire surface thereof, the comminuted material at one end of said surface covering substantially one half thereof being of different color from the opposite end or half of said surface. 45

8. As an article of manufacture, a shingle having a coating of comminuted material over one entire surface thereof, whereby either end of said shingle may be exposed to the weather and protected by said material, 50 said coating being of different colors on the opposite end portions of said surface whereby to obtain roofs of different colors from the same stock of shingles.

In testimony whereof I have affixed my 55 signature in presence of two witnesses.

FREDERICK C. OVERBURY.
